TYPEWRITING MACHINE

Original Filed March 9, 1923

Patented Mar. 30, 1926.

1,578,292

UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed March 9, 1923, Serial No. 623,824. Renewed May 1, 1925.

To all whom it may concern:

Be it known that I, JESSE A. B. SMITH, a citizen of the United States, residing in Stamford, in the county of Fairfield and 5 State of Connecticut, have invented certain new and useful Improvements in Typewriting Machines, of which the following is a specification.

This invention relates to typewriting machines, and more particularly to means for 10 typing stencil-cards.

In the co-pending application of A. G. F. Kurowski, No. 622,909, filed March 5, 1923, the platen is rotated by means of a handle 15 projecting outwardly from the cylindrical surface of the platen at one side of the typing zone for the stencil-cards, and the feed-rolls are cast off by means of a shaft above and to the rear of the platen and a 20 finger-piece on said shaft adjacent the initial card-inserting position of the platen-rotating handle, so that, when a card is inserted between the platen and the cast-off feed-rolls, the feed-rolls may be restored and the 25 platen rotated by one hand of the typist, only a slight movement of the hand being necessary to shift it from the cast-off finger-piece to the platen-rotating handle.

The present invention relates to means for 30 increasing the speed of operation by automatically controlling the feed-roll cast-off means, and to means for improving the operation in other respects.

According to the present embodiment of 35 the invention, the shaft by which the feed-rolls are cast off is provided with an arm having an open-ended slot into which projects a pin on the platen-rotating handle when the platen is in its initial position for card-insertion. The platen-rotating handle 40 is also mounted upon the platen so as to have lost motion thereon, and, upon movement of the platen-rotating handle from its rearmost position through the range of its lost motion, the cast-off shaft will be rotated to restore the feed-rolls, and, upon further actuation 45 of the platen-rotating handle, the pin will be withdrawn from the slot and the platen rotated to insert the card. Upon withdrawal of the card and restoration of the platen to its initial position, the pin will be brought into the mouth of the open-ended slot and further rearward movement of the platen-rotating handle will actuate the feed-roll cast-off shaft to cast off the feed-rolls. 55

To enable the typing on the stencil-cards to be seen more readily, provision may be made of a black stencil-card backing of suitable material, such as celluloid. The stencil-cards are usually moistened preparatory to 60 typing, and it is found that typing on the stencil-cards is seen more readily when a black backing is used than when the usual white backing is used.

The stencil-cards are sometimes warped 65 so that their bottom edges bow outwardly from the platen and have a tendency to catch on a type-bar-guide. To overcome this difficulty, provision may be made of suitable means, such as a wire card-guide 70 arched over the type-bar-guide and supported by inserting its ends into holes in a type-bar-segment. The card-guide may be flared forwardly above the type-bar-guide, so as to direct the lower edge of the downwardly-inserted 75 stencil-card between the type-bar-guide and the platen.

Other features and advantages will hereinafter appear.

In the accompanying drawings,

Figure 1 is a front elevation, showing the invention applied to so much of an Underwood standard typewriting machine as is necessary for the purpose of illustration.

Figure 2 is a sectional side elevation, showing the feed-rolls cast off, and a stencil-card in gaged position.

Figure 3 is a view similar to Figure 2, but with the platen-rotating handle swung forwardly sufficiently to restore the feed-rolls, preparatory to rotating the platen.

Figure 4 is a perspective view of a black backing-strip for use on the platen.

Figure 5 is a view similar to Figure 3, but with a stencil-card partly inserted.

Figure 6 is a view similar to Figure 5, but showing the stencil-card completely inserted to receive typing.

Figure 7 is a fragmentary sectional view, showing the backing-strip secured to the 100 platen.

A platen or platen-core 11 is supported by means of a platen-axle 12, journaled in the ends 13 of a platen-frame 14, comprising a rear paper-table 15, a rod 16, upon which paper-fingers (not shown) are usually mounted, and a rod 17 connecting the ends 13 beneath the platen.

Inasmuch as the machine is particularly intended for typing or cutting stencil-cards 110

18, only the central portion of the platen-core 11 is covered by an envelope 19 of suitable material, such as rubber, and serrated bands or rings 20 are secured to the platen-core 11 at each side of the envelope 19 in position to engage the edges of a stencil-card 18. To hold the stencil-card 18 in suitable engagement with the serrated bands 20, provision is made of feed-rolls 21 mounted on the forward ends of levers 22, pivoted by means of screws 23 on plates or arms 24 mounted at the rear of the platen on a rod 25, secured on the ends 13 of the platen-frame by screws 26 and on a rod 16 on which paper-fingers are usually mounted.

Adjustment of the plates 24 may be obtained by means of members 27 encircling the rod 16 adjacent the plates 24 and secured thereto by means of screws 28. To obtain such adjustment, the plates 24 fit loosely on the rod 16 and the screws 28 fit loosely in openings in the members 27, so as to permit the plates 24 to be shifted relatively to the members 27 and secured thereto by the screws 28.

The arms of the levers 22 at the rear of the screws 23 extend rearwardly and downwardly, and are provided at their rear ends with pins 29, to be controlled by cams 30 on a shaft 31, journaled in the plates 24. Each of the cams 30 comprises an incline 32, and a depression 33 at the forward end of the incline. When the cams are in the positions shown in Figure 2, the feed-rolls are cast off, and, when the cams 30 are in the position shown in Figure 3, the feed-rolls are permitted to be pressed against the bands 20 by means of springs 34 engaging pins 35 on the levers 22, and adjustably connected with plates 24 by means of devices 36, disclosed more fully in said co-pending application.

At the front or delivery side of the platen, the card 18 is guided to the platen by side-edge guides 38, each comprising a back plate 39, formed by the inturned forward end of the corresponding arm 24, a spacer 40 which engages the extreme edge of the card, and a resilient front plate 41, which is provided with a cutout 41^a to accommodate the adjacent lever 22 and feed-roll 21, to permit the latter to be pressed against the adjacent serrated band 20. A narrow extension 42 of the plate 41 extends downwardly and rearwardly, and at its lower end curves around a shaft 43, supported in brackets 44, projecting downwardly from the rod 17.

It is customary to wet the stencil-cards before typing, since better results are obtained under such conditions. According to the present invention, use is made of a black backing-strip 45, of suitable material for stencil typing, such as celluloid, the backing-strip being secured in position by retaining plates 46 and 47, secured to the platen by

screws 48, as shown in Figure 7. It has been found that, especially in connection with wet stencil-cards, the black celluloid enables the typing to be read more easily.

The platen is rotated for card-insertion by means of a handle 49, projecting from the cylindrical surface of the platen, and, after the insertion of a card, the platen 11 may be line-spaced by means of a finger-wheel 50 on one end of the platen-axle 12, or by line-spacing mechanism including a ratchet-wheel 51, fixed on the platen-axle 12, an actuating pawl 52, and a pawl-carrying slide 53, mounted on one end 13 of the platen-frame.

In said co-pending application, the platen-rotating handle is fixed directly on the platen, but, according to the present invention, the platen-rotating handle 49 is mounted to swing about a pivot 54 on an upright flange or plate 55 of a bracket 56, secured to the platen by means of screws 57. The movement of the handle 49 with reference to the flange 55 is limited by pins 58 projecting from the flange 55 on opposite sides of the handle 49. Such provision of lost motion for the handle 49 relative to the flange 55 is utilized to cast off and restore the feed-rolls 21 while the platen is in its initial card-inserting position determined by a fixed pin 59 in engagement with one end of a slot 60 in a cap 61 secured to the right-hand end of the platen 11. The pin 59 is shown, in Figure 2, in engagement with one end of the slot 60 to determine the initial card-inserting position, and in engagement with the other end of the slot, in Figure 6, to determine the limit of the card-inserting movement of the platen 11.

The automatic control of the feed-rolls 21 is effected by means of a pin 62, projecting from the side of the handle 49, and an arm 63, fixed on the shaft 31 and provided with a slot 64 to receive the pin 62. The sides of the slot 64 are substantially parallel throughout the greater part of their length, but, at the outer end of the slot, the upper side of the slot is provided with an outwardly-inclined portion 65, and the opposite side of the slot is provided with an inclined portion 66, to facilitate movement of the pin 62 into and out of the slot 64.

When the parts are positioned as shown in Figure 2, a stencil-card 18 may be inserted through the guides 38 and gaged by a ledge or gage 67, projecting outwardly from the upper edge of the retaining plate 47 for the backing-strip. Movement of the handle 49, from its Figure 2 position to its Figure 3 position, will produce no effect on the platen 11, but will serve, by means of the pin 62, to rotate the shaft 31 sufficiently to permit the rolls 21 to respond to the action of the springs 34, and grip the stencil-card 18 against the serrated bands 20.

Further movement of the handle 49 in the same direction will serve to advance the platen and card as indicated in Figure 5, the platen finally being checked by means of the pin 59 engaging the other end of the slot 60, as shown in Figure 6. The card 18 will then be in position for typing thereon by means of types 68 on type-bars 69.

After typing the first line on the stencil-card, the platen may be line-spaced, as previously described, and, upon the completion of the typing on the card, the card may be grasped by the typist and drawn out of the machine, and the platen 11 may be restored to its Figure 2 position. In the movement of the platen from its Figure 6 position to its Figure 3 position, the pin 62 will be brought into the outer end of the slot 64, and, upon shifting the handle 49 rearwardly to its Figure 2 position, the feed-rolls 21 will be cast off. It will be evident that, if the handle 49 be swung upwardly and rearwardly from its Figure 6 position, it will engage the upper pin 58 and turn the platen to its Figure 2 position, the pin 62 entering the slot 64, as the handle approaches its Figure 2 position and turning the shaft 31 to cast off the feed-rolls 21.

The stencil-cards are sometimes warped, so that the bottom edges bow outwardly from the platen and tend to catch on a type-bar-guide 70, mounted on a type-bar-segment 71. To prevent such interference, provision is made of a wire card-guide 72, looped over the type-bar-guide and supported by having its ends set into holes in the type-bar-segment 71. As shown in Figure 2, the card-guide is flared outwardly above the type-bar-guide 70 so as to guide the lower edge of an inserted stencil-card back of the type-bar-guide.

Variations may be resorted to within the scope of the invention, and portions of the improvements may be used without others.

Having thus described my invention, I claim:

1. In a typewriting machine, a platen, means to rotate the platen, means to predetermine the position to which the platen is rotated, feed-rolls to run on the platen, and feed-roll cast-off means rendered effective at the conclusion of the rotation of the platen to said predetermined position by said rotating means.

2. In a typewriting machine, a platen, means to predetermine the extent of rotation of the platen in line-feeding direction, feed-rolls running on the platen during the line-feeding operation, and feed-roll cast-off means rendered effective at the conclusion of the rotation of the platen in a line-feeding direction to said predetermined position.

3. In a typewriting machine, a platen, means to rotate the platen, means to pre-

determine the position to which the platen is rotated, feed-rolls to run on the platen, and feed-roll cast-off means operated by said platen-rotating means and rendered effective at the conclusion of the rotation of the platen in line-feeding direction to said predetermined position, said cast-off means being rendered ineffective at the backward rotation of the platen by said rotating means.

4. In a typewriting machine, a platen, feed-rolls to run on the platen, feed-roll cast-off means, a stop therefor, means for rotating the platen, and means actuatable by the platen-rotating means for automatically controlling the cast-off means as the platen moves to and leaves said stop.

5. In a typewriting machine, a platen, feed-rolls to run on the platen, feed-roll cast-off means, a handle movable in one direction to rotate the platen to insert a work-sheet downwardly at the front of the platen, and in the opposite direction to rotate the platen to its initial position preparatory to the insertion of a new sheet, and means operable by said handle during the latter part of its movement to position for inserting a work-sheet, to cast off the feed-rolls to permit the lower edge of the work-sheet to be inserted between the feed-rolls and the platen, and, during the first part of its inserting movement, to throw on the feed-rolls so as to draw the work-sheet downwardly into the machine.

6. In a typewriting machine, a platen, feed rolls to run on the platen, feed-roll cast-off means, a handle movable in one direction to rotate the platen to insert a work-sheet downwardly at the front of the platen, and in the opposite direction to rotate the platen to its initial position preparatory to the insertion of a new sheet, means operable by said handle during the latter part of its movement to position for inserting a work-sheet, to cast off the feed-rolls to permit the lower edge of the work-sheet to be inserted between the feed-rolls and the platen, and, during the first part of its inserting movement, to throw on the feed-rolls so as to draw the work-sheet downwardly into the machine, and means to gage said sheet preparatory to being gripped by the feed-rolls and inserted into the machine.

7. In a typewriting machine, a platen, a platen-frame, feed-rolls to run on the platen, feed-roll cast-off means, a platen-rotating handle mounted on the platen, and movable relatively thereto and means on the platen-frame actuated by the platen-rotating handle at its relative movement for controlling said cast-off means.

8. In a typewriting machine, a platen, feed-rolls to run on the platen, feed-roll cast-off means, and a platen-rotating handle

mounted on the platen for independent movement to cast off and restore the feed-rolls.

9. In a typewriting machine, a platen, a platen frame, means to limit the movement of the platen in opposite directions, feed-rolls to run on the platen, feed-roll cast-off means on said platen-frame, and a platen-rotating handle on said platen, connectible, by movement of the platen to one of its limiting positions, to the cast-off means to control the same.

10. In a typewriting machine, a platen, means to limit the movement of the platen in opposite directions, feed-rolls to run on the front of the platen, feed-roll cast-off means, and a platen-rotating handle on said platen, having means to engage and actuate said cast-off means as it approaches its limit of movement in swinging the front of the platen upwardly and rearwardly, and to release the cast-off means in the beginning of its movement to insert a card downwardly at the front of the platen.

11. In a machine for typing cards in rapid succession, a revolute platen, means to limit the movement of the platen in accordance with the requirements of the cards to be typed, feed-rolls to press the edges of the cards against the platen, feed-roll cast-off means, a platen-actuating handle pivoted on the platen at one side of the card-typing zone, stops for limiting the movement of said handle relative to the platen but permitting lost motion, and feed-roll cast-off means comprising a member to be engaged by said handle when the platen is turned to card-inserting position, and actuatable by the handle in its lost-motion movement to cast off the feed-rolls for the insertion of the lower edge of a card between the rolls and the platen, and releasable by the lost-motion movement of the platen-actuating handle in the opposite direction preparatory to completely inserting the card by continued movement of the handle.

12. In a typewriting machine constructed for rapid insertion and withdrawal of work at the front of the machine, a revolute platen, a platen-actuating handle movable in a plane perpendicular to the axis of the platen, means for limiting the movement of the handle relative to the platen but providing for lost motion, feed-rolls to run on the platen, and feed-roll cast-off means including a shaft above and to the rear of the platen and an arm fixed on the shaft and having an open slot and a pin on said handle to enter said slot when the platen is turned to its limiting position in a line-feed

direction, so that the handle when moved to its rearmost position will cast off the feed-rolls, and when moved forwardly through the range of its lost motion will effect restoration of the feed-rolls to effective position without shifting the platen.

13. In a typewriting machine, a revolute platen, means to limit the movement of the platen in both directions, a plate projecting from the platen substantially in a plane perpendicular to the axis of the platen, a platen-actuating handle pivoted on said plate, stops on said plate to be engaged by said handle when moved from its central position, feed-rolls to run on the platen, feed-roll cast-off means, and means actuatable by said handle for controlling said cast-off means when the platen is substantially in its limiting position for card insertion, said controlling means comprising a pin projecting laterally from said handle and a pivotally-mounted member having a slot to receive said pin when the platen is moved substantially to its initial position, said member being movable to cast off the feed-rolls by movement of the platen-actuating handle to its extreme rear position, and being movable to restore the feed-rolls to effective position upon movement of the platen-actuating handle into engagement with the forward stop preparatory to rotating the platen by the continued forward movement of the handle.

14. In a typewriting machine, a platen, a handle for turning the platen to insert a work-sheet downwardly at the front of the machine and in the opposite direction to eject the work-sheet, a feed-roll to press the work-sheet against the platen, and means actuatable by said handle for casting off the feed-roll to permit the work-sheet to be positioned for insertion by the platen, and for throwing on the feed-roll upon movement of the handle to rotate the platen in the direction to insert the work-sheet.

15. In a typewriting machine, the combination of a platen, feed-rolls to run on said platen, a bracket secured directly to said platen, and a finger-piece pivoted on said bracket to release said feed-rolls.

16. In a typewriting machine, the combination of a platen, feed-rolls to run on said platen, a bracket secured directly to said platen, a finger-piece pivoted on said bracket to release said feed-rolls, and stops on said bracket to limit the movement of said finger-piece about its pivot, said finger-piece after it meets the stops being effective to rotate the platen to feed a work-piece.

JESSE A. B. SMITH.
